(57) **CLAIM**

The ornamental design for a liquid precision discharge machine, as shown and described.

DESCRIPTION

FIG. 1 is a front view thereof, showing a liquid precision discharge machine of my new design;

FIG. 2 is a rear view thereof;

FIG. 3 is a right side view thereof;

FIG. 4 is a left side view thereof;

FIG. 5 is a top plan view thereof;

FIG. 6 is a bottom plan view thereof; and,

FIG. 7 is an oblique view thereof;

In the drawings, the broken lines depict portions of the liquid precision discharge machine that form no part of the claimed design. The single dotted line indicates only the boundary between the claimed portions and the unclaimed portions. This article is a device to dispense liquid materials such as cream solder, silver paste, epoxy resin, and liquid crystal materials at high speed and with high accuracy onto surfaces such as electronic substrates, glass substrates, and wafers.
